UNITED STATES PATENT OFFICE.

MAURICE ORIGET, OF ARROCHAR, NEW YORK.

METHOD AND MEANS FOR VAPORIZING HEAVY OILS.

1,370,476.

Specification of Letters Patent. Patented Mar. 1, 1921.

Application filed June 4, 1918. Serial No. 238,100.

To all whom it may concern:

Be it known that I, MAURICE ORIGET, a citizen of the United States, residing at Arrochar, in the county of Richmond and 5 State of New York, have invented certain new and useful Improvements in Methods and Means for Vaporizing Heavy Oils, of which the following is a specification.

My invention relates to a method and 10 means of vaporizing kerosene and other heavy oils, or other liquid hydrocarbons, etc., for use in an internal combustion motor, or for other purposes.

The relatively higher cost of gasoline and 15 other light oils has made this a great necessity, and numerous devices have been suggested for this purpose. By the application of my method, a simple attachment can be inserted between the carbureter and the 20 manifold of an internal combustion motor designed for the use of gasoline, as for instance in an automobile, whereby the carbureter can be caused to run with kerosene or other heavy oil, etc.

25 A preferred embodiment of my invention is diagrammatically shown in the annexed description and drawings, in which Figure 1 is a front elevation partly in section, Fig. 2 is a top view,

30 Fig. 3 is an enlarged view partly in section illustrating a modification, and

Fig. 4 is a front elevation partly in section showing another modification.

If an ordinary gasoline carbureter is 35 caused to operate with kerosene or the like, the oil is not vaporized at the ordinary temperature of the air with proper efficiency especially if the weather is rather cold. As a result, the kerosene is borne along in the 40 current of air sucked through the carbureter in the form of fine drops which leads to the well-known evils apparent in former devices of this character, such as difficulty in starting the engine, keeping it running, 45 smoking, excessive carbon deposits, etc. In addition, in former devices, the surplus of unconsumed kerosene left in the cylinder at each explosion ran down between the piston and cylinder into the crank case, and dis- 50 solved the lubricating oil.

According to my invention the mixture of air and kerosene which may be vaporized to a slight extent but is present largely in the form of minute drops is dashed against 55 a series of surfaces which are preferably porous, so that they absorb the drops of

kerosene and cause them to spread out by capillary attraction, exactly as a piece of blotting paper absorbs a drop of water and causes it to spread out. These porous surfaces which can be made of asbestos for example, are heated by suitable means, so that the absorbed kerosene is instantly raised to a suitable temperature for being immediately vaporized and carried off by the current of air. The area of the absorbing surfaces may be made as large as desired, as if there is an excess of area, this will produce no bad effect as the porous surfaces cannot possibly absorb more kerosene than is sprayed on to them from the carbureter. The use of asbestos is preferred, although my invention is not limited thereto, because it is not only porous, absorbing the kerosene instantly, but it is also a non-conductor of heat, so that the vaporized kerosene and air are not heated too high, and the explosive mixture does not enter the cylinders in too expanded a condition.

As the carbureter permits a delicate adjustment of the amount of kerosene sprayed in, an exact regulation of the quantity of kerosene vaporized is possible.

Such a method is entirely different in principle and operation from numerous devices in which asbestos was caused to dip into a pool of kerosene and absorb it and raise it by capillary attraction and then give it all to a current of air by suitable means. Practical tests have shown that it was impossible to regulate the amount of kerosene so absorbed and vaporized under the widely varying conditions present in the operation of an internal combustion motor, so that in order to be able to start the engine, a mixture that was far too rich for any practical purposes was later supplied to the cylinders.

According to my invention only the unvaporized kerosene is sprayed or impacted with considerable force upon the porous surfaces so that the drops of kerosene are instantly spread out and instantly vaporized because of the heat and any desired amount of asbestos or equivalent porous surfaces may be provided without the need of any regulation other than the customary regulation of the carbureter. Besides, in my method the kerosene preferably does not contact at all with the means for heating the asbestos, but only with the warmed asbestos.

The carbureter, which is conventionally

represented by the part 1 may be of any suitable type at present known, and is only diagrammatically shown because my invention is neither directed nor limited to any particular type, although in practical tests I have found the Holley carbureter satisfactory. The mixture of air and vaporized and unvaporized kerosene is led through the pipe 2 controlled by the valve 6 into the attachment 8 which is interposed between the carbureter 1 and the pipe 14 having the valve 31, and leading to the manifold of the engine. The attachment 8 which may have any desired shape is divided into three parts by partitions 11 and 12 which are connected by means of tubes 10 open at the top and bottom. The compartment 7 is connected to the exhaust pipe 15 having the valve 30 so that the heated exhaust gases from the engine or heated gases from any other source may be passed through it, through the tubes 10 as indicated by the arrows, to heat them and thereby heat the asbestos wicks 13 which are of a porous character, and which surround the tubes 10. The exhaust gases pass out of the open compartment 16 to the exhaust pipe at the rear of the automobile, or any other convenient place.

Since the tubes 10 are arranged in the staggered relation shown in Fig. 2, the gases in the attachment 8 are imparted movements at right angles to the main direction of flow, and no unvaporized drops of kerosene can pass through without being absorbed and then vaporized.

I prefer to arrange the exhaust pipe near the entrance end of the apparatus, so that the tubes 10 there are hotter than the others. The air and kerosene do not contact with the heated tubes which are much hotter than the outer surfaces of the wicks, but only with the outer surface of the asbestos, as the drops of kerosene are so small and the porous surface is of such area, that the drops of kerosene do not penetrate to an undesirable extent into the asbestos. However, even if the drops of kerosene penetrate the asbestos to the heated tubes, they are vaporized so rapidly that overheating is prevented.

Hence, even if the engine is running at high speed, so that a large amount of exhaust gases are emitted, and the tubes 10 become highly heated, the temperature of the outside surface of the wicks 13 is not raised to an undesirable extent, because the attachment may be allowed to radiate heat freely, so that the slow thermal conductivity of the asbestos prevents it from becoming overheated, and the mixture of air and hydrocarbon passing through it does not become too hot and too expanded. Otherwise, the said mixture might expand so much as to cause a back pressure in the carbureter

and the engine would not only receive too dilute a mixture just when it requires a rich mixture, but the apparatus would not function at all. Experience has shown that the small amount of heat necessary to vaporize kerosene can be secured even if the engine is running at very low speed, so that the exhaust gases do not yield much heat, and that it can be run through the same range of speeds with the same flexibility as if gasoline were being used, if the spray is maintained continuously, so that the wicks 13 do not become dry.

That this is the action is shown by actual tests as the compartment 7 is so hot that it cannot be touched by the human hand while the device is operating, while the walls of the central compartment are much cooler and the walls of the bottom compartment 16 while a little warmer than those of the central compartment are much cooler than those of the compartment 7. This demonstrates that the tubes 10 absorb the heat of the exhaust gases and that this heat is not radiated because of the asbestos wicks 13 which retain all the heat so that the exhaust gases are much cooled when they enter the compartment 16.

If desired, the engine can be started by pouring some gasoline first into the carbureter 1 until the exhaust gases are sufficiently hot to permit the use of kerosene, and the device may be operated with gasoline alone with improved efficiency.

In Fig. 3 I have shown wires 17, suitable for heating, by means of electricity supplied through leads 20 and 21 to these wires which may be embedded in the asbestos, or wound in a spiral externally around the asbestos as shown in Fig. 4 so that the asbestos and tubes may be heated by an electric current provided from any suitable source in order to start the engine.

I prefer to cause the attachment 8, to lose heat so rapidly, either by conduction or radiation, or by directing a current of air thereon, that the temperature of the outside of the wicks is but little above that at which the kerosene is freely and rapidly vaporized by the current of air sucked in through the carbureter and attachment. This current of air also assists in keeping down the temperature of the outside of the wicks. In this manner all cracking of the hydrocarbon and all carbon deposits are avoided, although a short stop makes it necessary to heat the attachment 8 again for starting purposes. The thickness of the wicks and the radiation from or the cooling of the attachment may be varied to provide a suitable temperature in the central compartment of the attachment, although experience has shown that the same attachment is operative for both gasoline and kerosene. This operation is assisted by the fact that the gases passing

- through the central compartment of the attachment travel in a circuitous path, and move tangentially with respect to the wicks 13. 65
- 5 When mounted on an automobile between the carbureter and the manifold, the attachment may be caused to lose heat so freely that the gases passing through the central compartment always remain at the 10 right temperature. Since the wicks are heated only by the hot metal tubes 10, the flow of the gases through the central compartment is not disturbed as if gaseous heating means were used, and the air is caused 15 to pass tangentially through the pores of the asbestos, as it moves around the wicks and tubes. The attachment is preferably made of metal, although any suitable material may be used. 20
- 20 I have shown a preferred embodiment of my invention in a diagrammatic manner but it is obvious that numerous changes and refinements could be introduced without departing from its spirit and I do not wish to 25 be limited to the details herein described. Thus the attachment 8 could be heated by any desired means to start the operation of the device, which preferably has thick metal walls and the carbureter could be directly 30 coupled to the attachment, without the pipe 2.
- I claim:
1. A method of vaporizing a liquid hydrocarbon, which consists in spraying a mixture thereof with air upon heated porous material which absorbs it, the temperature of said porous material being sufficiently high to cause the rapid vaporization of the said fuel, the temperature of the said 35 porous material being kept below the point at which there will be any substantial combustion of the said fuel during the vaporization and the said intermixing, so that the mixture of air and vaporized fuel is at a 40 lower temperature than the source of heat wherefrom the said porous material is heated. 45
  2. A method of vaporizing a liquid fuel which consists in spraying a mixture thereof with air upon porous material which absorbs it, and heating the said porous material on the side opposite to that upon which the spray of fuel falls, the temperature of the porous material being sufficiently high 50 to cause the rapid vaporization of the said fuel and its intermingling with the said air, the said temperature being below the point at which substantial combustion of the said fuel will occur during the said intermingling, so that the temperature of the intermingled fuel and air is less than that of the source of heat by means of which the said 55 porous material is heated. 60
  3. A method of vaporizing a liquid fuel which consists in spraying a mixture thereof with air upon porous material, which absorbs it and heating the said porous material on the side opposite to that upon which the spray of fuel falls, the temperature of the porous material being sufficiently high 65 to cause the vaporization of the said fuel by said air, the said porous material being a poor conductor of heat, so that it has a lower temperature on the side on which the said spray falls than on the heated side, 70 the temperature of the said porous material being below the point at which any substantial combustion of the said fuel takes place, the temperature of the mixture of vaporized fuel and air being less than that of the source of heat by means of which the said 75 porous material is heated. 80
  4. A method of vaporizing a liquid fuel, which consists in spraying a mixture thereof with air on porous material, which is a poor conductor of heat, and heating the said porous material on the side opposite to that upon which the spray falls, the drops of sprayed fuel being absorbed by said material and being vaporized before they reach 85 the heated side of said porous material, the temperature of vaporization being less than the temperature of the source of heat, so that there is no substantial combustion of the said fuel during the said vaporization 90 and the mixture of vaporized fuel and air have a temperature lower than that of the source of heat by means of which the said 95 porous material is heated. 100
  5. A method of vaporizing a liquid fuel, which consists in spraying a mixture thereof with air on a porous material which absorbs the fuel, heating the side of the said porous material opposite that upon which the fuel falls by means of a heated non-porous body, and maintaining the said side on which the said fuel falls at a lower temperature than said body, the said drops of fuel being vaporized before they contact 105 with said heated body, the temperature of the said porous material being below the point at which any substantial combustion of the said fuel can take place, so that the temperature of the intermingling vaporized fuel and air is below that of the source of 110 heat by means of which the said porous material is heated. 115
  6. A method of vaporizing a liquid fuel, which consists in spraying a mixture thereof with air on a porous material which is a poor conductor of heat and absorbs said fuel, heating the side of said porous material opposite to that upon which the fuel falls and is absorbed by means of a heated non-porous body, which receives a variable 120 amount of heat, and depriving the said heated body of its heat, so as to always maintain 125 that portion of the said porous material

which absorbs said fuel at a temperature below that at which any substantial combustion can take place, so that the mixture of vaporized fuel and air remains at a temperature below that of the source of heat from which said porous material is heated.

7. A method of vaporizing a liquid fuel, which consists in spraying a mixture thereof with air upon a series of heated porous bodies which absorb said fuel, and which are arranged in staggered relation, so that the air and spray travel in a circuitous path between said bodies, the temperature of the said porous bodies being below the point at which any substantial combustion of the said fuel can take place, the temperature of the intermingling vaporized fuel and air being below the point of the source of heat

by means of which the said porous bodies are heated.

8. A method of vaporizing a liquid fuel for use in an internal combustion engine, which consists in heating porous material by means of the exhaust gases from the said engine and causing the said fuel to contact with the said heated porous material while in the presence of air, the temperature of the region of vaporization being maintained below the point at which any substantial combustion of the fuel can take place during its vaporization, so that the mixture of vaporized fuel and air has a temperature below that of the said exhaust gases.

In testimony whereof I hereunto affix my signature.

MAURICE ORIGET.
